UNITED STATES PATENT OFFICE

MALCOLM RAYMOND, OF HOMER CITY, PENNSYLVANIA

ADHESIVE-PLASTER-DISPENSING DEVICE

Application filed February 21, 1927. Serial No. 169,805.

An object of this invention is to provide an adhesive plaster dispensing device of novel, simple and efficient construction whereby gauze covered adhesive plaster in rolls may be supported and manipulated in a manner to permit pieces of the plaster to be easily and quickly removed from the gauze, whereby the plaster may be kept clean and sterile and ready for instant use, whereby the handling of the plaster and the protecting gauze is reduced to a minimum in hospitals, dressing stations and other places where large quantities of plaster are used, and whereby left over ends of pieces of plaster removed from the gauze may be easily and quickly returned thereto and subsequently removed therefrom for use.

A further object of the invention is to provide a novel and advantageous method of dispensing gauze covered adhesive plaster from rolls thereof with the aid of a suitable mechanical device.

With the foregoing and related objects in view the invention consists of the elements and the combinations of them and of the method of dispensing the plaster hereinafter described and claimed.

In the accompanying drawings illustrating the invention,

30 Figure 1 is a front view, partly broken away, of a dispensing device, embodying my invention, showing the adhesive plaster and its gauze thereon.

35 Figure 2 is a side view thereof applied to a supporting wall, the wall being shown in section.

Figure 3 is a transverse section through the device, on line 3—3 of Fig. 1.

40 Figure 4 is a sectional detail, showing the receiving shaft and adjuncts.

Figure 5 is a transverse section through the receiving shaft showing the gauze attached to one of the spurs or hooks of the shaft, and showing a piece of the adhesive plaster partially stripped from the gauze.

Referring to the drawings, 2 designates a frame which may be of any suitable shape and size for its intended purpose. As herein illustrated this frame 2 comprises vertically-arranged side bars 4 and 5 and upper

and lower brackets 6 and 7, respectively, which are secured to the bars 4 and 5 and which hold them in spaced parallel relation. The brackets 6 and 7 extend back from the bars 4 and 5 and they are provided with holes 8 for the reception of suitable screws 9 by means of which the frame may be secured to a wall of a room in a hospital or other place where it is desired to use the device, such wall being shown in section, at 10, in Fig. 2 of the drawings.

Supported by the upper and lower end portions of the side bars 4 and 5 of the frame 2 and extending transversely between them are two horizontally-arranged, parallel shafts 11 and 12, respectively. The upper shaft 11 is provided to receive and rotatably support a roll of gauze covered or protected adhesive plaster 13, and the lower shaft 12 is provided to receive and have wound upon it the gauze 14 from the roll of gauze and plaster 13, as will be hereinafter described.

The upper or delivery shaft 11 has a collar 15 adjustably and removably secured to one end portion thereof by means of a set screw 16; and the other end portion of the shaft 11 has a collar 17 suitably secured thereto. The respective ends of the shaft 11 project outwardly from the collars 15 and 17 and are seated in downwardly extending slots or sockets 18 in the side bars 4 and 5. The slots 18 have open upper ends to permit the ends of the shaft 11 to be readily inserted into and removed from the same. The fixed collar 17 has a projection or extension 19 thereon which fits against the side walls of the slot 18 in the bar 5 to prevent the shaft 11 from turning.

Slidable on the shaft 11 adjacent to the collar 17 is a loose collar 20, and encircling the shaft 11 between the fixed collar 17 and loose collar 20 is a spring 21 which tends to force the loose collar 20 toward the fixed collar 15 previously referred to.

The roll of adhesive plaster 13 is rotatably mounted on the delivery shaft 11 between the collars 15 and 20 thereon, and the loose collar 20 is pressed against one end of the roll 13 by the spring 21, the pressure of which presses the opposite end of the roll 13 against

the fixed collar 15. The pressure of the spring 21 is such as to prevent the roll 13 from turning freely on the shaft 11 and to provide the desired tension for the adhesive 5 plaster 22 and the gauze 14 by which it is carried when they are drawn from the roll 13.

The lower or receiving shaft 12 is mounted to turn in suitable bearings in the lower end portions of the side bars 4 and 5 of the frame 10 2. One end portion of the shaft 12 extends outwardly from the side bar 5 and carries a crank 23 provided with a handle 24 by means of which the shaft 12 may be manually turned. The other end portion of the shaft 15 12 extends outwardly from the side bar 4 and has a collar 25 fixed thereon. A spring 26 encircling the shaft 12 is interposed between the bar 4 and collar 25 and tends to move the shaft 12 longitudinally to move the 20 crank 23 toward the side bar 5. The shaft 12 has a collar 27 fixed thereon adjacent to and inwardly of the side bar 4; and arranged between the collar 27 and the bar 4 is a plate or block 28 having a facing 29 of leather or 25 other suitable friction material adapted to bear against the collar 27. The shaft 12 penetrates the plate 28 and its facing 29, and one end portion of the plate 28 is loosely connected to the bar 4 by a screw 30 in a manner to 30 prevent the plate 28 from turning with the shaft 12 and to permit the plate to be moved toward the collar 27. The plate 28 is adapted to be forced toward the collar 27 by a suitable hand operated screw 31 which is screwed into 35 and through the bar 4 and has its inner, rounded end seated in a socket in the plate 28. The screw 31 may be adjusted by turning it to force the plate 28 and its leather facing 29 against the collar 27 and against 40 the yielding action of the spring 26 until the necessary friction is produced for the desired retardation of the turning of the shaft 12.

The shaft 12 is provided with two or more pointed spurs or hooks 32 for engagement 45 with the free end portion of the gauze 14, whereby the gauze may be wound upon the shaft and thereby drawn from the roll 13 when the shaft 12 is turned by hand.

In using the device the shaft 11 is removed 50 from the frame 2 and the collar 15 is removed from the shaft. The roll 13 of gauze protected adhesive plaster is then placed upon the shaft 11 and the collar 15 is returned to the shaft and secured in place thereon by 55 means of the screw 16 after the collars 15 and 20 and the interposed roll 13 have been forced by hand against the action of the spring 21 until the collars 15 and 20 act with suitable pressure against the ends of the roll. The 60 shaft 11 is then returned to the frame 2 with the parts of the device in the position shown in the drawings. The free end portion of the gauze 14 of the roll 13 is then drawn down to the shaft 12 and engaged with the hooks 65 or spurs 32 thereon. The shaft 12 is then

given a slight turn in the direction of the arrow in Fig. 2 to start the winding of the gauze upon the shaft and to stretch the gauze 14 carrying the adhesive plaster 22 between the roll 13 and the shaft 12. The friction 70 produced by the collars 15 and 20 against the ends of the roll 13, and produced by the leather facing 29 against the collar 27 of the shaft 12 holds the gauze 14 in a taut condition between the roll 13 and shaft 12 and 75 permits the adhesive plaster 22 to be removed from the gauze 14, without turning the roll 13 or shaft 12, by stripping the plaster 22 from the gauze 13 upwardly from the lower end of the plaster. Strips of plaster of different widths are stripped from the gauze by tearing the plaster longitudinally as it is stripped upwardly after the line of tear is first started by a cut made by a pair of scissors or other cutting device, and, after a 80 desired piece of plaster has been stripped upwardly from the gauze the plaster is cut transversely from the main body thereof by a pair of scissors or other cutting tool and is ready for use. If the entire piece of plaster 85 stripped from the gauze is not used, the surplus thereof may be plastered back upon the gauze and thereby kept clean and in proper condition for use at another time.

After all or nearly all of the plaster carried by that part of the gauze extending between the roll 13 and the shaft 12 has been stripped from the gauze, the crank 23 is operated to turn the shaft 12 to wind the gauze 14 upon the shaft and thereby 95 unwind the gauze 14 and plaster 22 carried thereby from the roll 13 until a desired fresh area of plaster is presented upon that portion of the gauze which extends between the roll 13 and the shaft 12. The plaster of this fresh area is then stripped from the gauze as previously explained and the 100 plaster is used as needed, and so on until the entire roll 13 of plaster and gauze has been 105 used.

After the entire roll of plaster has been used, the gauze 14 may be removed from the shaft 12 by turning it oppositely to the direction indicated by the arrow in Fig. 2. During the unwinding of the gauze from the 110 shaft 12 the friction of the leather facing 29 against the collar 27 may be relieved by loosening the screw 31 to permit the shaft 12 to turn freely.

I claim as my invention:

In an adhesive plaster dispensing device and in combination, a frame, a delivery shaft removably mounted on the frame, a collar removably secured on the shaft, a collar 115 slideable on the shaft toward and from the first named collar, said shaft and said collars being removable as a unit from the frame, yielding means carried by the shaft and constructed to act yieldingly against the slideable collar when it is moved away from the first 120

named collar, means to prevent the shaft from turning, a receiving shaft journaled on the frame in spaced relation to the delivery shaft, and means operable to turn the receiving shaft.

5 In testimony whereof I affix my signature.

MALCOLM RAYMOND.
